AIR SCOOP

Alex Kraus, Los Angeles, Calif., assignor to California Custom Accessories Manufacturing Company, Gardena, Calif.

Filed Mar. 18, 1968, Ser. No. 11,012

Term of patent 14 years

(Cl. D14—6)

FIGURE 1 is a side elevational view of the air scoop;
FIGURE 2 is a top view of the air scoop;
FIGURE 3 is a bottom view of the air scoop;
FIGURE 4 is a front view of the air scoop; and
FIGURE 5 is a rear view of the air scoop.

The dominant features of my design reside in the portions shown in full lines.

I claim:

The ornamental design for an air scoop, substantially as shown and described.
